UNITED STATES PATENT OFFICE.

JOHN T. WARING, OF NEW YORK, N. Y.

METHOD OF AND APPARATUS FOR MAKING HAT-BODIES AND OTHER FABRICS OF CARDED FIBERS AND DISINTEGRATED FIBERS.

SPECIFICATION forming part of Letters Patent No. 277,636, dated May 15, 1883.

Application filed August 31, 1882. (No model.)

To all whom it may concern:

Be it known that I, JOHN T. WARING, of the city and county of New York, in the State of New York, have invented certain new and useful Improvements in the Method of and Apparatus for Making Hat-Bodies and other Fabrics of Carded Fibers and Disintegrated Fibers, of which the following is a specification.

This invention relates to the manufacture of hat-bodies and other fabrics of carded fibers and disintegrated or separated fibers by obtaining a deposit of disintegrated or separated fibers upon a bat or lap of carded fibers, the principal object being to provide for the manufacture of such fabrics of wool and fur, and especially to utilize in such manufacture the cheaper kinds of fur-stock.

The invention consists, principally, in obtaining such deposit of fur or separated or disintegrated fiber by the agency of a current or currents of air caused to pass through the bat or lap of wool or carded fiber from the side on which the fur or disintegrated fiber is deposited.

The invention also consists in means, hereinafter described and claimed, employed for thus obtaining such deposit, and for completing the fabric produced by said bat or lap and said deposit thereon.

The nature of my invention will be fully explained by aid of the following specification and the drawings annexed, which form part of the same.

Referring to the drawings, Figure 1 is a plan view, and Fig. 2 is a central vertical section on the line $x-x$ of Fig. 1, of a machine adapted to carry out my invention in the manufacture of hat-bodies. Fig. 3 is a transverse section on the line $x-x$ in Fig. 2. Fig. 4 is a similar section on the line $y-y$ of the same figure, and Fig. 5 is a detached view of a regulating-valve in the end of a perforated cylinder supporting the forward end of an endless perforated apron which supports the bat or lap.

In each of the views similar letters of reference are employed to indicate corresponding parts wherever they occur.

A A is the main framing, and B the main or driving shaft, which receives motion from a pulley, B', driven by a band or otherwise.

C represents an endless perforated or reticulated apron or belt formed of wire-cloth or other suitable material, mounted on rollers or cylinders C' C², having shafts c c', supported in bearings on the main framing A. The roller or cylinder C', with its endless apron C, is driven by means of a shaft, D, mounted at an angle in bearings carried by the main framing A. At its lower end the shaft D is provided with a bevel-pinion, D', which gears into a bevel-pinion, D², keyed onto the end of the driving-shaft B, while at its upper end it is provided with a worm, D³, which gears into a worm-wheel, s, affixed on the shaft c of the cylinder C'. 55 60 65

E represents the doffer-cylinder, and E' the doffer-comb, of a carding-engine, which may be of any ordinary or suitable construction, adapted to supply a bat or lap of wool or carded fiber, F, to the upper surface of the endless traveling apron C for treatment, as hereinafter described. 70

Upon one end of the shaft c is mounted a driving-pulley, G, which by means of a belt, g, communicates motion to a pulley, G', on a shaft, h, mounted in bearings carried by the main framing A. 75

Upon the shaft h is affixed a roller or cylinder, H, and a pulley, h', upon which works an endless band, h², which also passes over and drives a pulley fast on the upper one, I, of the two feed-rollers I I'. 80

H² is an endless apron, which is carried by the roller or cylinder H, before described, and a roller, H', the said apron being driven by the roller or cylinder H. This endless apron H² is arranged at a slight angle, as shown, and is adapted to receive on its upper surface, h³, a layer of fur-stock, which is distributed evenly on the same by hand or by suitable mechanism. 90 (Not shown.) The fur-stock, having been so distributed on the apron H², is conducted thereby to and between the pair of feed-rollers I I', the upper one, I, of which is driven by a pulley, i², affixed on the shaft h of the cylinder H. The fur is then conducted by the rollers I I' to a picker-cylinder, J, armed with the necessary teeth j, operated by a belt, j², driven by a pulley, j³, mounted on the main driving-shaft B. The picker-cylinder J is of a character and con- 95 100

In some cases it may not be necessary to combine the picker and the trunk, or either of them, directly with the bat-carrying apron, as the fur may be picked or disintegrated in a separate machine, and delivered to or above the bat on the bat-carrying apron by any suitable means.

Having thus described my invention, what I claim, and desire to secure by Letters Patent, is—

1. The within-described improvement in the art of manufacturing hat-bodies or other fabrics from carded fibers and disintegrated fibers, consisting in depositing disintegrated fur or fiber into and upon the surface of a bat or lap of carded fiber by means of air drawn through the bat or lap from that side thereof on which the disintegrated fiber is supplied, substantially as and for the purpose described.
2. The within-described improvement in the art of manufacturing hat-bodies or other fabrics from carded fibers and disintegrated fibers, consisting in depositing disintegrated fur or fiber into and upon the surface of a bat or lap of carded fiber by means of air drawn through the bat or lap from that side thereof on which the disintegrated fiber is supplied, and afterward rubbing the deposited disintegrated fiber into the bat or lap, substantially as and for the purpose described.
3. In machinery for making hat-bodies and other fabrics of carded fibers and disintegrated fibers, the combination, with the doffer of a carding-engine, a perforated or reticulate bat-carrying apron, C, and a device for supplying disintegrated fiber, of the feed-rollers I I', picker J, trunk K, and exhaust box or chamber N, substantially as and for the purpose described.
4. The combination, in a machine for making hat-bodies or other fabrics of carded fibers and disintegrated fibers, of a perforated or reticulated apron or carrier for carrying a bat or lap of carded fiber, a device for delivering disintegrated fiber on the surface of said bat or lap, an exhaust apparatus for producing

the circulation of air through the said bat or lap from the side on which the disintegrated fiber is delivered thereon, and a rotating conical former for the reception of the said bat or lap and the disintegrated fiber deposited thereon, substantially as herein described.

5. The combination, with a perforated or reticulated apron or carrier for carrying a bat or lap of carded fiber and a deposit of disintegrated fiber, and a rotary conical former for the reception of the said bat or lap and deposited fiber, of a reciprocating rubbing device arranged behind the said conical former for the purpose of rubbing the disintegrated fiber into the bat or lap of carded fiber, substantially as herein described.

6. In machinery for making hat-bodies and other fabrics of carded fibers and disintegrated fibers, the combination, with a perforated or reticulated bat-carrying device, C, and a device for supplying disintegrated fiber, of the feed-rollers I I', picker J, trunk K, exhaust box or chamber N, cones or formers P P, and bed-rollers p' p'', substantially as and for the purpose described.

7. The combination, with the bat-carrying apron of a machine for making hat-bodies or other fabrics of carded fibers and disintegrated fibers, of a perforated or reticulated cylinder, C², provided with an internal blast for the purpose of facilitating the pulling or drawing off of the combined fabrics, substantially as shown and described.

8. The combination, with the bat-carrying apron of a machine for making hat-bodies or other fabrics of carded fibers and disintegrated fibers, and a perforated or reticulated cylinder, C², provided with an internal blast for the purpose of facilitating the pulling or drawing off of the combined fabric, of a pressure-regulating valve, e*, substantially as and for the purpose described.

JOHN T. WARING.
